UNITED STATES PATENT OFFICE.

GEORGE H. FORSYTH, OF CHICAGO, ILLINOIS.

DRAFT-RIGGING MECHANISM.

SPECIFICATION forming part of Letters Patent No. 766,610, dated August 2, 1904.

Application filed April 20, 1903. Serial No. 153,538. (No model.)

To all whom it may concern:

Be it known that I, GEORGE H. FORSYTH, a citizen of the United States, residing at Chicago, in the county of Cook and State of Illinois, have invented certain new and useful Improvements in Draft-Rigging Mechanism, of which the following is a specification.

In the growth and development of the art of draft-rigging appliances for railway-cars there has arisen within recent years a demand for draft-rigging devices which will permit a greater freedom of lateral movement on the part of the draw-bar when a train of cars is passing around a curve, this demand growing out of the fact that where but a very limited lateral play is provided for straining and injury of the members of the car and not infrequently breakage of the draw-bar or some of its associated parts frequently results. Where such increased lateral play is permitted, however, it is essential that means be provided for automatically positioning the draw-bar for coupling purposes in order that the draw-bars of adjacent cars shall always lie in positions favorable to coupling on any character of track.

Recent improvements in draft-rigging mechanism have in several instances taken the general form of pivoting the draw-bar coincident with the king-bolt or so as to swing in the line of a radius of a circle of which the king-bolt is substantially the center and connecting it laterally to the truck-bolster, whereby the angular movement of the bolster relatively to the car-body automatically maintains the draw-bar in a position at right angles to the truck-bolster, thus bringing the draw-bars of two endwise adjacent cars into a position more nearly approaching a straight line when on a curve, the connections to the truck being extensible to enable the draw-bars to assume under draft a position in longitudinal alinement coincident with the line of draft in passing around a curve.

Such an arrangement as that last described while constituting somewhat of an advance over the older art nevertheless falls short of an improved organization wherein two endwise adjacent draw-bars are constantly main-

tained in a straight line, which is coincident 50 with the line of draft while the cars are on track of the same character, whether it be a plain curve, a reverse curve, or a straight section of track. Obviously where the draw-bar is maintained constantly at right angles to the 55 truck-bolster coöperating draw-bars on endwise-abutting cars necessarily form an angle with each other on a plain curve and on a reverse curve may be parallel, or substantially so, but out of line with each other, in neither 60 of which positions exist the most effective conditions for automatic couplings, such conditions requiring endwise alinement of the draw-bars.

In a companion application filed concurrently herewith, Serial No. 153,537, I have presented a device of this character wherein the object of the invention is stated to be to provide an improved organization wherein endwise adjacent draw-bars are maintained in 70 substantially a straight line coincident with the line of draft, whether the cars be coupled or uncoupled and whatever the character of the track beneath them, and in the said application I show a mechanism for carrying out this object 75 wherein the draw-bar is pivotally connected to the car-body at a point coincident with the axis of the king-bolt, said mechanism including a novel draw-bar-controlling means operated from and by the angular movement of the truck relatively to the car-body, through which there is imparted to the draw-bar an angular movement relatively to the longitudinal median line of the car which exceeds the angular movement of the truck-frame 80 relatively to the bolster of the car-body, such angular movement, furthermore, being proportional to the degree of curvature of the track and such as to maintain the draw-bar substantially coincident with the line of draft 85 on any character or formation of track. My present invention has this same general object in view and embodies the same broad principle of operation as applied to a construction wherein the draw-bar instead of being pivoted at a point coincident with the axis 90 of the king-bolt, or substantially so, is pivotally mounted relatively to the car-body at a

point more or less in advance of the king-bolt, this latter construction having an advantage over the former in that a given angular swing of the draw-bar does not require 5 as much space at the end of the car to accommodate the same as in the former construction and another advantage in that it does not necessitate such a long draw-bar.

In the companion application above referred 10 to I have also disclosed and claimed a novel mechanism for cushioning the buffing and pulling strains on the draw-bar, said mechanism including as the novel feature thereof follower-blocks laterally insertible through the 15 casing containing the cushioning devices after the latter have been assembled. A minor object of my present invention is to provide a novel and improved form of such follower-blocks in association with novel means for retaining them in place.

Referring to the accompanying drawings, Figure 1 is a side elevation of a draft-rigging and draw-bar-controlling device constituting one form of mechanism in which my present 25 invention may be carried out. Fig. 2 is a top plan view of Fig. 1. Fig. 3 is a transverse section through the draft-timbers, showing the immediate supporting and controlling mechanism of the draw-bar in rear end view. Fig. 4 is a transverse section on the line 4-4 30 of Fig. 1 looking in the direction of the arrow; and Figs. 5 and 6 are diagrammatic views illustrating the principle and mode of operation of my invention on plain and reverse curves, 35 respectively.

Referring to the drawings, 10 designates the bottom or floor of the end portion of a railway-car, 11 the draft timbers or beams, and 12 the end sill, pendent from which latter 40 is the usual carry-iron 13.

14 designates the truck-bolster; 15, the bottom center plate mounted thereon; 16, the top center plate; 17, the body-bolster, and 18 the king-bolt passing through said parts and pivotally connecting the center plates.

19 designates the draw-bar, having extending inwardly from its rear end the usual strap or yoke 20. This yoke is surrounded and incased by a casing formed by a pair of oppositely-disposed channel-beams 21 and 22, the opposite side walls of which are cut out, leaving at the opposite ends of said beams inwardly-extending and meeting tongues 23 and 24, respectively, to the outer faces of which 50 are bolted transverse tie-plates 25 of a length equal to the combined height of the channel-beams and of a width coextensive with the width of the tongues to which they are secured. The rear ends of the channel-beams 55 are continued rearwardly in the form of upper and lower extensions 21^a and 22^a, respectively, which embrace the upper and lower faces of a bridge-piece 26, rigidly bolted to and extending between the draft timbers or

beams 11, the upper extension 21^a resting directly upon the top face of said bridge-piece and being pivotally secured thereto by means of a headed bolt 27, passed from beneath through registering holes in said extension members and bridge-piece, said bolt being retained in place by any suitable means—as, for instance, by a collar or washer 28 and a cotter-pin 29.

30 designates the draft and buffer spring located within the yoke and at its opposite 75 ends abutting a pair of what I term "follower-shells" 31, these latter being either castings or simply short sections of channel-iron cut to a suitable length to fit between the abbreviated side flanges of the channel-beams constituting the members of the casing, and 32 designates as an entirety the follower-blocks, which when in operative position are contained within said follower-shells. Each 80 of these follower-blocks is made in the form 85 shown in Fig. 4, with a head 32^a at one end and a hole 32^b, formed through its opposite end, adapted to receive a locking-pin 33. From the foregoing it will be seen that the follower-blocks 32 are readily insertible laterally of the casing, and when in place the head portions 32^a and opposite apertured end portions project sufficiently to abut the combined edges of the tongues 23 24 and tie-plates 25, the heads of the follower-plates preventing 90 their accidental displacement in one direction, and the locking-pins 33 similarly preventing their displacement in the opposite direction.

The described combination of the draft and 100 buffer spring, the follower-shells, the follower plates or blocks, and the containing skeleton casing is set forth and claimed in my companion application, hereinabove referred to, my present improvements in this particular mechanism relating more particularly to the means 105 for locking the follower plates or blocks in operative position.

Referring now to the mechanism for automatically controlling the draw-bar, 34 designates a pulley, preferably in the nature of a sprocket-wheel, which is rigidly secured in a horizontal slot or mortise 35, formed through the central part of the truck-bolster, said pulley being so disposed as to be concentric with 115 the axis of the king-bolt 18. On the pivot-bolt 27 and resting upon the enlarged head 27^a at the lower end thereof is a pulley or sprocket-wheel 36 of considerably reduced diameter as compared with the pulley 34. Secured to or formed integral with the upper 120 face of the pulley 36 is an arm 37, extending radially of the pulley and underlying the containing-frame of the draft-rigging, said arm having mounted on its outer end a saddle 38, 125 pivoted centrally to the arm and having its upwardly-extending ends embracing the sides of the frame of the draft-rigging. The pul-

leys 34 and 36 are connected by endless operating belt or chain 39. The operation is as follows: When a car is passing around a curve, the truck-bolster 14 undergoes an angular movement relatively to the superposed car-body, which thus imparts a partial rotation to the large pulley 34. In view of the fact that the smaller pulley 36 is, through the supporting bridge-piece 26, to 10 which it is pivoted, fixed relatively to the car-body, such partial rotation of the pulley 34 communicates to the smaller pulley through the belt or chain 39 a partial rotation on its own axis, which partial rotation, by reason of the difference in diameter between the two pulleys, produces a much greater angular movement of the smaller pulley than of the larger pulley. This angular movement swings the arm 37 through a 15 corresponding angle, which arm through the saddle 38 swings the draw-bar and its draft-rigging also to one side of its normal position, such angular movement of the draw-bar itself being equal to the angular movement of the 20 arm 37 by reason of the fact that they are both carried on a common pivot-bolt, and the pulleys 34 and 36 are so proportioned as to relative size as to insure that the angle from the longitudinal median line of the car described by the draw-bar in this movement 25 shall exceed the angular movement described by the truck-bolster relatively to the body-bolster, and the increase of the former angle over the latter is such as will serve to maintain the draw-bar coincident, or substantially so, with the line of draft, which in this case extends between adjacent pivot-bolts 27 on two endwise adjacent cars on all kinds of track. This angular lead of the draw-bar 30 over the truck-bolster will be proportional to the degree of curvature of the track by reason of the fact that the angular movement of the truck-bolster relatively to the car-body is obviously always proportional to the degree 35 of curvature of the track, the extent of rotation of the large pulley 34 is always proportional to the angular movement of the truck-bolster, the rotary movement of the smaller pulley 36 is always proportional to the rotary 40 movement of the larger pulley, and the angular movements of the arm 37 and of the draw-bar (which are the same) are always proportional 45 to the rotary movement of the pulley 36.

In Figs. 5 and 6 of the drawings I have 50 diagrammatically illustrated the operation and advantages of my invention. In Fig. 5 the two lines $a'b$ and $a'b'$ represent median lines of two endwise adjacent cars on a section of track which forms a plain curve. As 55 is shown by the diagram, these two lines intersect at a point x between the adjacent ends of the cars at a considerable angle. In the same figure are shown a pair of lines $c'd$ and $c'd'$, which are drawn at right angles to

the truck-bolsters at the respective adjacent 60 ends of the car, which bolsters of course lie coincident with radii $e'f$ and $e'f'$ of the curve, and it will be seen that these two lines $c'd$ and $c'd'$ intersect each other at a point y , which is within the angle formed at the point 65 x , and constitutes a greater angle, but is nevertheless less than an angle of one hundred and eighty degrees. These lines $c'd$ and $c'd'$ represent the positions of draw-bars such as are maintained for coupling purposes at right 70 angles to the truck-bolsters of their respective cars, from which it will be seen that even in the arrangement last mentioned the draw-bars are when uncoupled caused to stand at somewhat of an angle to each other, and consequently not in the most favorable position 75 for automatic coupling. In said drawings the numeral 19 designates a pair of endwise adjacent draw-bars pivoted relatively to their respective car-bodies at points in advance of 80 the king-bolts in accordance with the preceding description of the mechanism illustrated in Figs. 1 to 4 and occupying the positions in which they are automatically maintained by the hereinabove-described mechanism, which 85 positions are such as to place and maintain the draw-bars in longitudinal alinement, which 90 is obviously their most favorable position for coupling purposes.

In Fig. 6. I have diagrammatically illustrated the operation of my invention when two contiguous cars occupy positions on a reverse curve. In this figure, as in Fig. 5, the lines $a'b$ and $a'b'$ designate the median lines of the cars; but these lines, instead of intersecting, as in Fig. 5, lie parallel or substantially so. The lines $c'd$ and $c'd'$, as in Fig. 5, designate lines extending at right angles to the truck-bolsters, which latter are coincident with radii $g'h$ and $i'k$ of the two plain 100 curves which form the compound or reverse curve; but these two lines $c'd$ and $c'd'$ also instead of intersecting, as in Fig. 5, lie offset in parallel lines or substantially so. In this figure also 19 designates the two coöperating 105 draw-bars occupying the positions in which they are automatically maintained by my invention, in which positions it will be observed said draw-bars are in longitudinal alinement and coincident with the line of draft between 110 their pivotal connections to their respective cars, which latter is obviously their most favorable position for coupling purposes.

When two adjacent cars are on a straight section of track, the draw-bars are maintained 115 in alinement in positions which are both coincident with the line of draft and at right angles to their respective truck-bolsters.

While I have shown a specially-designed 120 construction of draft-rigging mechanism, it must be evident that the fundamental principle of my invention, which is the providing 125 of a draw-bar-controlling mechanism to main-

tain the draw-bar constantly in substantial coincidence with the line of draft, may be employed in conjunction with any construction of draw-bar wherein the latter is allowed to have a pivotal lateral movement.

In my companion application, hereinabove referred to, I have claimed mechanism whereby the general object of this invention is carried out irrespective of the point at which the draw-bar is pivotally connected to the car, and hence I do not in this application claim such mechanism broadly; but believing myself to be the first to provide mechanism for accomplishing this object in connection with a draw-bar pivoted in advance of the king-bolt

What I do claim, and desire to secure by Letters Patent, is as follows:

1. The combination with a car-body, a truck-frame, and a draw-bar capable of angular movement, of an endless connection between said truck-frame and draw-bar adapted to swing the latter sidewise in either direction during angular movement between the truck and car-body.

2. The combination with a car-body, a truck-frame and a draw-bar pivotally connected to said car-body in advance of the king-bolt, of connections between said truck-frame and draw-bar for actuating the latter laterally and imparting thereto on curves an angular movement relatively to the longitudinal median line of the car constantly proportional to the degree of curvature of the track.

3. The combination with a car-body, a truck-frame and a draw-bar pivotally connected to said car-body in advance of the king-bolt, of connections between said truck-frame and draw-bar for actuating the latter laterally and imparting thereto on curves an angular movement relatively to the longitudinal median line of the car greater than the angular movement of the truck-frame relatively to the car-body and constantly proportional to the degree of curvature of the track.

4. The combination with a car-body, a truck-frame and a draw-bar pivotally connected to said car-body in advance of the king-bolt, of connections between said truck-frame and draw-bar for actuating the latter laterally and imparting thereto on curves an angular movement relatively to the longitudinal median line of the car greater than the angular movement of the truck-frame relatively to the car-body, and which is also constantly proportional to the degree of curvature of the track and such as to always maintain the draw-bar substantially coincident with the line of draft.

5. The combination with a car-body, a truck-frame and a draw-bar pivotally connected to said car-body in advance of the king-bolt, of a pulley carried by said truck-frame and so connected thereto as to be rotated by the an-

gular movements of the truck-frame relatively to the car-body, another pulley rotatably mounted on the pivotal axis of the draw-bar, a driving connection between said pulleys, and connections between said last-named pulley and the draw-bar through which the rotative movement of the former imparts an angular lateral movement of the latter.

6. The combination with a car-body, a truck-frame and a draw-bar pivotally connected to the car-body at a point in advance of the king-bolt, of a pulley so mounted on the truck-frame as to be rotated by the angular movement of the latter relatively to the car-body, another pulley rotatably mounted on the pivot of the draw-bar, a driving-belt connecting said pulleys, and connections between said last-named pulley and the draw-bar through which the rotative movement of the former imparts an angular lateral movement to the latter exceeding the angular movement of the truck-frame relatively to the car-body.

7. The combination with a car-body, a truck-frame and a draw-bar pivotally connected to said car-body at a point in advance of the king-bolt, of a pulley rigidly mounted on the truck-frame concentric with the axis of the king-bolt, another pulley rotatably mounted on the pivot-bolt of the draw-bar, a driving-belt connecting said pulleys, and connections between said last-named pulley and the draw-bar through which the rotative movement of the former imparts an angular lateral movement to the latter exceeding the angular movement of the truck-frame relatively to the car-body.

8. The combination with a car-body, a truck-frame and a draw-bar pivotally connected to said car-body at a point in advance of the king-bolt, of a pulley rigidly mounted on the truck-frame concentric with the axis of the king-bolt, another pulley rotatably mounted on the pivot-bolt of the draw-bar, a driving-belt connecting said pulleys, a radially-extending arm rigid with said last-named pulley, and a saddle carried by said arm and itself constituting a seat for the draw-bar, substantially as described.

9. The combination with a car-body, a truck-frame and a draw-bar pivotally connected to said car-body at a point in advance of the king-bolt, of a pulley mounted rigid with the truck-bolster and concentric with the axis of the king-bolt, another pulley rotatably mounted on the pivot-bolt of the draw-bar, a driving-belt connecting said pulleys, a radially-extending arm rigid with said last-named pulley, and a saddle pivotally mounted on said last-named arm and itself seating the draw-bar, substantially as described.

10. The combination with a pivoted draw-bar and means for actuating the same laterally, of a draw-bar guide interposed between said draw-bar and said actuating means, said guide

being pivotally mounted coaxially with the pivot of the draw-bar, substantially as described.

11. The combination with a pivoted draw-bar and means for actuating the same laterally, of a draw-bar guide interposed between said draw-bar and said actuating means, said guide being pivotally mounted coaxially with the pivot of the draw-bar and presenting substantially the same surface of contact thereto throughout the movements of the latter.

12. The combination with a draw-bar and its yoke, of a skeleton casing in which said

yoke is slidingly contained, an elastic medium, and a pair of laterally-insertible follower-blocks in said casing the ends whereof overhang the side walls of the latter, one end of said follower-blocks being enlarged to form a head and the other end being apertured, and locking-pins passed through said apertures, substantially as described.
